G. E. BARNHART

GOLF CLUB

Filed Oct. 14, 1926

INVENTOR.
GEORGE E. BARNHART
BY *A. B. Bowman*
ATTORNEY

UNITED STATES PATENT OFFICE.

GEORGE E. BARNHART, OF PASADENA, CALIFORNIA.

GOLF CLUB.

Application filed October 14, 1926. Serial No. 141,644.

My invention relates to golf clubs, more particularly to means of securing the shafts of golf clubs to the heads thereof.

In golf clubs now in use, the shafts are made of wood as well as of steel tubing. Although the golf clubs with wooden handles provide greater flexibility and resiliency both longitudinally and torsionally, the same break frequently at the portions directly secured to the heads. Steel or other metal shafts, although more durable, also break frequently at the portions secured to the heads. Steel or other metal shafts, as heretofore constructed, provide less longitudinal flexibility than wooden shafts and very little torsional flexibility and resiliency.

The objects of my present invention are: first, to provide a steel shaft for golf clubs which will have the torsional flexibility and resiliency of the wooden shaft of golf clubs and still have durability superior to the conventional steel shaft; second, to provide a golf club having a steel shaft in which the shaft is secured at its extreme end to the head of the club and reinforced intermediate its ends near its secured end in the form of a pivot means adapted to take the initial bending moment and considerably relieve the danger of breaking of the shaft from the head immediately at the secured portion; third, to provide a shaft for golf clubs which is provided intermediate its ends with longitudinal slots for weakening the shaft at one portion to permit greater flexibility in twisting and longitudinal bending, as well as to provide greater torsional and longitudinal resiliency; fourth, to provide a golf club having a long ferrule provided with a recessed portion at its interior and intermediate its ends and a fulcrum or bearing portion in its interior and outwardly from the recessed portion, the shaft of the club extending through the ferrule and secured to the head at the base of the ferrule, the fulcrum or bearing portion providing reinforcement for said shaft and fulcrum means for longitudinal bending, and said recessed portion providing clearance for the bent shaft within the ferrule; fifth,

to provide novel, efficient and economical means for repairing old golf clubs and transforming old clubs into new by merely cutting off the shank from the old head and welding, brazing, soldering, or otherwise securing a special ferrule thereto; sixth, to provide a steel shaft which may be slotted longitudinally to any desired degree to provide any desired flexibility and resiliency; seventh, to provide a golf club of this class whereby the shock often imparted through the shaft to the hands of the player, will be reduced to a minimum; and, eighth, to provide as a whole a novel means of securing a shaft to the head of a golf club, providing a simple and efficient club and one which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a fragmentary side elevational view of the head end of a metal head golf club, showing certain parts and portions thereof broken away and in section to facilitate the illustration; Fig. 2 is a transverse sectional view of the ferrule and shaft taken through 2-2 of Fig. 1; Fig. 3 is an enlarged fragmentary sectional elevational view of a slightly modified form of securing the ferrule and shaft to the head of a golf club; and, Fig. 4 is a fragmentary sectional elevational view taken through the median line of the club, showing a slightly different means of construction.

Like characters of reference refer to similar parts and portions throughout the several views of the drawings.

The golf clubs illustrated in Figs. 1 and 3 of the drawings show the clubs reconstructed from conventional clubs. The head, indicated by 1 in Fig. 1, is provided in the conventional club with an outwardly

diverging shank, shown by dotted lines designated by S in Fig. 1. In order to adapt the head to a steel shaft, or any other metal shaft, to my construction, the shank is shortened to the line indicated by A and provided with an offset, indicated by B. Against the end of the shank and at the offset portion B thereof, is positioned the base end of the tubular ferrule 2. This ferrule 2 may be brazed, soldered, or welded to the head member 1.

The ferrule 2 may be tapered to smaller dimensions toward its upper end to reduce weight and also provide for greater flexibility. The interior of the ferrule 2 is provided with a bore 2^a considerably larger than the diameter of the shaft 3 extending therethrough, said bore extending upwardly at substantially the same diameter as the offset portion at the upper end of the shank of the head member. The upper end of the bore of the ferrule, indicated by 2^b, is considerably constricted and loosely engages the rod or shaft 3 several inches from its lower end for reinforcing the shaft. Said constricted portion 2^b of the bore of the ferrule is also rounded and tapers divergently on curved lines toward the upper end of the ferrule, as shown. Thus, when the shaft 3 is bent, the same will bend about the portion 2^b which serves as a fulcrum and will bend slightly, but uniformly, from its lower end to the fulcrum portion 2^b. The bore 2^a permits considerable bending of the shaft. The lower end of the shaft 3 may be variously secured to the head member in a central recess 1^a in the shank thereof, such as by pouring molten brass, or other metal into the hole in which the shaft is positioned, as indicated by 4 in Fig. 1.

The shaft 3, shown in the drawings, is made of tapered steel tubing and is provided in its walls at the portion positioned between the upper end of the shank of the head member and the constricted portion of the ferrule with longitudinal slots 3^a. Said slots are adapted to weaken the shaft at said portion to such an extent as to provide torsional flexibility to any desired degree as well as to increase its longitudinal flexibility. By such slotting, the torsional and longitudinal resiliency is also increased. Such flexibility and resiliency may be varied by increasing or decreasing the number and size of the longitudinal slots in the shaft.

The structure shown in Fig. 3 is substantially the same as that illustrated in Fig. 1, except that the upper end of the shank of the head member and the base portion of the ferrule are beveled, as indicated respectively by 1^b and 2^c, so that the two members may be readily welded together and to the inner end of the shaft.

It will be here noted that instead of constructing the head member 1 and the ferrule

2 in separate pieces, as stated, the same may be made integrally, if desired.

In Fig. 4 of the drawings, the head member 1 and the ferrule 2 are shown as of integral construction with the space between the large bore 2^a and the shaft filled with lead, or other deadening material 5. It will be noted in this construction, the shaft 3 may be provided with its smallest diameter some distance from its inner end, as indicated by 3^b, so that the lead or other material 5 may readily retain the shaft in position.

In Fig. 4 of the drawings, the inner end of the shaft may be secured, if desired, to the head member in any suitable manner, such as by the pouring of molten brass 4 around the inner end of the shaft within the inwardly converging recess and through a hole from the outside of the head member. It will be noted if the shaft 3 is secured to the head member at its inner end, as stated, or by any other means, the lead or other metal or material 5 may be eliminated.

By either of the last mentioned constructions greater flexibility is obtained than by rigidly securing the outer end of the ferrule to the shaft, as in conventional construction. Also, by the former construction, in which lead is used for securing the shaft within the ferrule, the shock is somewhat deadened by the lead or other material 5.

Though I have shown and described a particular construction, combination and arrangement of parts and portions, and certain modifications thereof, I do not wish to be limited to this particular construction, combination and arrangement, nor to the modifications, but desire to include in the scope of my invention the construction, combination and arrangement substantially as set forth in the appended claims.

Having thus described my invention, what I claim as new and desire to secure by Letters Patent is:

1. In a golf club, a head member provided with a long ferrule, and a metallic shaft secured to said head member at the base of said ferrule, the portion of said shaft extending outwardly from the base of said ferrule being yieldably positioned within said ferrule to permit longitudinal twisting of said shaft within the same.

2. In a golf club, a head member provided with a long ferrule, and a metallic shaft secured to said head member at the base of said ferrule, the interior of said ferrule near the outer end thereof being provided with a pivot portion, the portion of said shaft extending outwardly from the base of said ferrule being yieldably positioned within the same and permitted to bend about the pivotal portion of the ferrule.

3. In a golf club, a head member having a

long ferrule, said ferrule being undercut in its interior and intermediate its ends, and a metal shaft secured to said head member at the base end of said ferrule and permitted

5 to freely move within said ferrule outwardly from its secured end.

4. In a golf club, a head member having a long ferrule, said ferrule being undercut in its interior and intermediate its ends, and a metal shaft secured to said head member at the base end of said ferrule, the interior of said ferrule, outwardly from said undercut portion, serving as a pivot for said shaft when being bent longitudinally, the undercut portion of said ferrule clearing the bent offset of said shaft.

5. In a golf club, a head member having a long ferrule, said ferrule being under cut in its interior and intermediate its ends, and a metal shaft secured to said head member at the base end of said ferrule, said shaft being provided at the end positioned within said ferrule with longitudinal slots whereby said shaft is weakened to permit axial twisting and longitudinal bending, and also to cause greater torsional and longitudinal resiliency.

6. In a golf club, a head member having a long ferrule, said ferrule being under cut in its interior and intermediate its ends, and a metal shaft secured to said head member at the base end of said ferrule, said shaft being provided at the end positioned within said ferrule with longitudinal slots whereby said shaft is weakened to permit axial twisting and longitudinal bending, and also to cause greater torsional and longitudinal resiliency, the interior of said ferrule outwardly from said under cut portion serving as a pivot for longitudinal bending of said shaft and for relieving the strain on the end of said shaft directly secured to said head member.

7. In a golf club, a head member having a long ferrule, the interior of said ferrule intermediate the outer and base ends thereof being recessed for clearance, and a metal shaft extending into said ferrule with its one end and secured at said end to said head member at the base of said ferrule, the outer portion of the bore of said ferrule, outwardly from said recessed portion, being of substantially the same diameter as the corresponding opposite portion of said shaft.

8. In a golf club, a head member having a long ferrule, the interior of said ferrule intermediate the outer and base ends thereof being recessed for clearance, and a metal shaft extending into said ferrule with its one end and secured at said end to said head member at the base of said ferrule, the outer portion of the bore of said ferrule, outwardly from said recessed portion, being of substantially the same diameter as the corresponding opposite portion of said shaft, said

bore being tapered outwardly in gradual curves providing a curved bending fulcrum for said shaft at a spaced distance from its secured end.

9. In a golf club, a head member having a short shank and a recess in its end, a shaft extended with its one end into the recess of the shank of said head member and engaging the walls of the recess, and a tubular ferrule positioned around said end of the shaft and secured at its one end to the end of the shank of said head member.

10. In a golf club, a head member having a short shank and a recess in its end, a shaft extended with its one end into the recess of the shank of said head member, and a tubular ferrule positioned around said end of the shaft and secured at its one end to the end of the shank of said head member, the outer end of said ferrule fitting loosely and engageably around said shaft to reinforce the same at a distance from the end positioned in said head member, said ferrule being recessed at its interior inwardly from its outer end to provide clearance for said shaft when subjected to bending stresses.

11. In a golf club, a head member provided with a socket and with a shaft, the latter being secured at its one end within the inner portion of the socket, the portion of the shaft near the outer end of said socket being freely movable within and relative to and about the outer end portion of said socket to prevent buckling of said shaft at the outer end of the socket.

12. In a golf club, a head member provided with a socket and with a shaft, the latter being secured at its one end within the inner portion of the socket, the bore at the outer end of said socket being outwardly divergent forming a fulcrum about which said shaft is flexed longitudinally when striking a ball with the golf club.

13. A ferrule for reinforcing the shaft connection of a golf club to the head thereof, comprising a long sleeve, the outer end of the bore thereof, through which the shaft is adapted to extend, being outwardly divergent to serve as a fulcrum for the longitudinal bending of said shaft relative to said ferrule.

14. A ferrule for reinforcing the shaft connection of a golf club to the head thereof, comprising a long sleeve, the outer end of the bore thereof, through which the shaft is adapted to extend, being outwardly divergent, and the portion of the bore positioned inwardly from said divergent portion being under cut to permit longitudinal bending of the shaft within the ferrule.

15. In a golf club, a head member provided with a long ferrule, and a metallic shaft extending with its one end in said ferrule and secured at said end therein, the interior of said ferrule, near the outer end

thereof, being provided with a pivot portion adapted to serve as a fulcrum for said shaft.

16. In a golf club, a head member provided with a ferrule, and a metallic shaft extending with its one end in said ferrule and secured at said end therein, the portion of the bore of the ferrule positioned in-

wardly from its outer end being undercut to provide clearance for the flexion of said ¹⁰ shaft within the ferrule.

In testimony whereof, I have hereunto set my hand at Los Angeles, California this 4th day of October 1926.

GEORGE E. BARNHART.

thereof, being provided with a pivot portion adapted to serve as a fulcrum for said shaft.

16. In a golf club, a head member provided with a ferrule, and a metallic shaft extending with its one end in said ferrule and secured at said end therein, the portion of the bore of the ferrule positioned in-

wardly from its outer end being undercut to provide clearance for the flexion of said shaft within the ferrule. 10

In testimony whereof, I have hereunto set my hand at Los Angeles, California this 4th day of October 1926.

GEORGE E. BARNHART.
